(No Model.)

G. TURNER.

CHIMNEY TOP.

No. 363,778.

Patented May 24, 1887.

UNITED STATES PATENT OFFICE.

GEORGE TURNER, OF SCHUYLER'S LAKE, NEW YORK.

CHIMNEY-TOP.

SPECIFICATION forming part of Letters Patent No. 363,778, dated May 24, 1887.

Application filed March 19, 1887. Serial No. 231,574. (No model.)

To all whom it may concern:

Be it known that I, GEORGE TURNER, a citizen of the United States, residing at Schuyler's Lake, in the county of Otsego and State of New York, have invented new and useful Improvements in Chimney-Tops, of which the following is a specification.

This invention relates to improvements in chimneys, referring more particularly to the formation of the tops thereof, its objects being to prevent the upper layers or tiers of brick from being displaced or broken and disfiguring or injuring the chimney thereby.

The invention consists in the construction and novel arrangement of a top embracing the upper end of the chimney, as hereinafter described, pointed out in the appended claims, and illustrated in the drawings.

In the accompanying drawings, Figure 1 represents a perspective view of a chimney having the improved top attached. Fig. 2 represents a vertical section on the line *xx* of Fig. 1. Fig. 3 represents a vertical section on the line *yy* of Fig. 1. Fig. 4 represents a detail sectional view showing how the small corner-offsets at the lower part of the top are inserted into the brick-work.

Referring to the drawings by letter, A designates a chimney, and B the top or casing, preferably of cast metal, secured upon the upper end thereof. The said casing consists of the four similar side pieces, C, and the top plate, D. The side pieces are beveled at their corners at angles of forty-five degrees, and secured together, to form a rectangular frame, E, having the circumferential depending flange *e*. In the tops of the corners formed by the flange *e* the frame E is provided with the offsets *e'*, triangular in plan view, which enter corresponding recesses in the brick-work of the chimney. Above the flange *e* the frame extends horizontally outward at *f*, and then rises vertically about the height of a brick at *F*. It then extends again horizontally outward at *g* and again vertically upward at *G*, but not quite so high as before. Upon the upper edge of the part *G* the plate *D* is laid, and bolts *d d* passed through openings therein and in the part *g* of the frame and the nuts *d'* screwed thereon below said part *g*. The upper ends of said openings in plate *D* are countersunk, so that

the heads of the bolts *d d* are flush with the upper surface of the plate, and the said surface is inclined downward from its central rectangular opening, *h*, to cause rain to run off its outer edge.

H is a flange that extends downwardly vertically from the opening *h* and surrounds the same, and *I* is a cover semicircular in cross-section and attached over the opening *h*, to prevent rain, snow, or hail from falling therein. The top extends outward on all sides somewhat beyond the frame, and is provided with a circumferential depending flange, *i*, to prevent water from entering.

In building the top of the chimney the same is inclosed by the frame *E*, the small triangular flanges being inserted into corresponding recesses in the brick-work at the lower surface of the second tier of brick from the top. The highest tier of brick is set sufficiently outward for the flange *H* to rest against its inner surface flush with the interior surface of the chimney below the top.

The top, as described, is of simple construction, and when secured to the upper end of the chimney will form a strong union therewith, as the small triangular flanges enter recesses in and are supported by the brick-work, and the top of the upper tier of brick supports the top plate, *D*. The frame *E*, moreover, cannot bind upon the chimney by contraction, as its interior does not fit closely thereon, the chimney-top being supported or held to the chimney, as described.

Having thus described my invention, I claim—

1. The herein-described chimney-top, consisting of four side pieces connected at their ends to form a rectangular frame, and a top plate secured to the upper edge of said frame, the frame being provided with a circumferential depending flange to fit upon the outside of the chimney, small triangular offsets within the corners of the depending flange adapted to enter corresponding recesses in the brick-work and a circumferential horizontal portion above said flange, and the top being provided with a flange depending from its central rectangular opening to enter and lie against the interior of the chimney, and being connected to the frame by bolts which pass through suit-

able openings in the plate and in the horizontal portion of the frame and are engaged by nuts below the latter, substantially as specified.

2. The combination, with a chimney, of the 5 rectangular frame E, provided with the flange e, the offsets e', entering corresponding recesses in the brick-work, and the horizontal portion g, having bolt-openings at its corners, the top plate provided with the chimney h, the flange 10 i, and the flange H, to enter the interior of the chimney, and the bolts d d, which pass through countersunk openings in the plate and bolt-openings in the part g of the frame and are engaged to nuts below said part, substantially 15 as specified.

3. The combination, with a chimney having its highest layer or tier of brick set a sufficient distance outward from the adjacent layer or

tier, of the plate D, having a central opening, h, and a flange depending therefrom and lying 20 against the inner surface of the first layer of brick, so as to be flush with the second layer thereof, and inclining downward on all sides from its central opening, the frame E, provided with the flange e, offsets e', and the horizontal 25 portion g, substantially as described, and connected to the top plate by bolts, and the cover attached to the top plate and standing over the opening therein, substantially as specified.

In testimony that I claim the foregoing as 30 my own I have hereto affixed my signature in presence of two witnesses.

GEORGE TURNER.
